(57) **CLAIM**

The ornamental design for a humeral component for shoulder arthroplasty, as shown and described.

DESCRIPTION

This application claims the benefit of U.S. patent application Ser. No. 14/069,154, which was filed on Oct. 31, 2013, is entitled Humeral Arthroplasty. The contents of U.S. application Ser. No. 14/069,154 are hereby incorporated by reference in its entirety as part of this application.

FIG. 1 is a front left perspective view of a humeral component for shoulder arthroplasty;

FIG. 2 is a back left perspective view of the humeral component for shoulder arthroplasty;

FIG. 3 is a back view of the humeral component for shoulder arthroplasty;

FIG. 4 is a front view of the humeral component for shoulder arthroplasty;

FIG. 5 is a right side view of the humeral component for shoulder arthroplasty;

FIG. 6 is a left side view of the humeral component for shoulder arthroplasty;

FIG. 7 is a top view of the humeral component for shoulder arthroplasty;

FIG. 8 is a bottom view of the humeral component for shoulder arthroplasty;

FIG. 9 is a cross sectional view of a left portion of the humeral component for shoulder arthroplasty taken along line 9-9 of FIG. 3; and,

FIG. 10 is a cross sectional view of a bottom portion of the humeral component for shoulder arthroplasty taken along line 10-10 of FIG. 3.
